UNITED STATES PATENT OFFICE.

WILLIAM H. WOODWARD, OF WACO, TEXAS.

BALING-PRESS.

No. 833,104.

Specification of Letters Patent.

Patented Oct. 9, 1906.

Application filed November 18, 1905. Serial No. 287,964.

To all whom it may concern:

Be it known that I, WILLIAM H. WOODWARD, a citizen of the United States, residing at Waco, in the county of McLennan and State of Texas, have invented new and useful Improvements in Baling-Presses, of which the following is a specification.

This invention relates to baling-presses; the object of the invention being to provide 10 an effective apparatus of this character which operates to solidly compress material without waste thereof and in a rapid manner.

A press including the invention can be advantageously employed for baling different 15 kinds of material, such as hay, cotton, &c.

In the drawings accompanying and forming a part of this specification I illustrate a simple form of embodiment of the invention, which to enable those skilled in the art to 20 practice said invention I will set forth in detail in the following description, while the novelty of the invention will be included in the claims succeeding said description.

In the drawings, Figure 1 is a side elevation of the improved baling-press. Fig. 2 is a top plan view of the same. Fig. 3 is a central longitudinal vertical section. Fig. 4 is a transverse section taken on the line 4 4 of Fig. 3. Fig. 5 is a detail view showing a 30 modified form of feeder-carrier.

Like reference characters refer to like parts throughout the several views.

The press illustrated in the drawings includes a baling-chamber, as 2, in communication with a plunger-box, as 3, the material to be compressed being delivered through the upper open side of the plunger-box, where it is delivered by a reciprocating plunger, as 4, into the baling-chamber 2, the outer end and 40 sides of the latter being open. The bales when made are ejected through the outer end of the baling-chamber 2.

The press may be mounted upon wheels, as 5, whereby it can be readily transported from 45 place to place. To the sides of the plunger-box 3 are fastened the beams 6, extending in parallelism outward from said box and connected at intervals to form a frame for supporting a plunger-actuating member, as 7. 50 The plunger-actuating member is shown as consisting of a gear of two similar sections, between which is pivoted the outer end of a connecting-rod or pitman 8, the inner end of said rod being jointed to the plunger 4. It 55 will be understood that when the gear-wheel 7 is rotated the plunger 4 will be reciprocated

through the medium of the connecting-rod or pitman 8 in the plunger box or casing 3. The shaft of the gear-wheel 7 is supported by suitable bearings upon the beams 6.

Meshing with the sections of the two-part gear 7 are pinions, as 9, the shaft of which is supported by suitable bearings upon the beams and carries a driving member, as 10, which is represented as consisting of a pulley or band-wheel. When the pulley or band-wheel is rotated, the plunger 4 through the intermediate mechanism will be moved back and forth in its box 3. Upon the sides and top of the plunger-box 3 are arranged outwardly-diverging plates, as 11, the sides of the box being joined by a plate, as 12. The three plates present, in effect, a hopper into which the material to be baled is delivered, the plates serving to prevent scattering of 75 such material.

Upon the forward movement of the plunger it is projected into the baling-chamber 2, so as to push the material into said baling-chamber, which material had been previously 80 supplied to the plunger-box in front of the plunger. Upon the backward movement of the plunger its box is left substantially open, so as to receive a mass of material in front of it. Upon the sides of the plunger-box 3 I 85 arrange spring-fingers, as 13, the free ends of which are inwardly bent to extend through slots or openings in the sides of the box. The fingers yield outwardly when material is forced into the baling-chamber by the advancing plunger. On the backward movement of the plunger the free ends of the fingers are projected inward into the plunger-box, so as to interpose stops across the plunger-box, which limit or prevent back motion 90 of the material from the baling-chamber into the plunger-box. The side edges of the plunger are notched to receive the free portions of the fingers as the plunger completes 95 its forward stroke.

Extending across the top of the plunger-box 3 is a rocking member, as 14, approximately cam shape in cross-section, the opposite ends of which are provided with journals supported for rocking motion by and extending through the side walls of the plunger-box. Fastened to the journals of the rocking member 14 are arms, as 15, to which are pivoted bars 16, headed at their lower ends, the bars extending between their ends through suitable guides, as 17, upon the sides of the box or casing 3. The bars are surrounded by coiled

springs 18, which bear at their ends against the guides 17 and heads of the bars, so as to maintain the rocking member 14 normally in its operative position with its lower edge below the plane of the under surface of the top of the baling-chamber. When, therefore, a mass of material is in the plunger-box 3 in front of the plunger and when the plunger is advanced, the mass of material will be moved forward with the upper side thereof against the lower edge of the rocking member 14. On the continued forward movement of the plunger the said rocking member is moved in an upward direction by the pressure of the moving mass thereagainst, whereby the arms 15 will be elevated to put, through the intermediate parts, the coil-springs 18 under compression. As soon as the plunger moves backward the rocking member will be relieved of pressure, so that the springs 18 can return the said rocking member to its original position.

As the plunger moves backward a feed device, as 19, becomes operative to double the material on itself, so that when the plunger again moves forward the material will be compressed in doubled-up sections or loops. The feed device 19 is operative in unison with the plunger 4, it being shown as connected in the present case with a carrier, as 20, which receives its motion from the plunger. The carrier is represented as consisting of an angle-lever pivoted between the ends of one of its branches between the posts or standards 21, which rise from the parallel beams 6. The feed device is suitably braced. To that branch of the angle-lever which is directly supported by the posts are connected links, as 22, jointed at their lower ends to the pivot of the joint 8^a, hereinafter more particularly described. I would state that the joint 8^a is between the plunger 4 and the pitman or connecting-rod 8. Upon the backward movement of the plunger the feed device 19 is projected downward into the plunger-box 3, so as to double the material on itself in advance of the plunger and to carry loose material into said box. As the plunger commences to move forward the feed device by reason of its connection with said plunger is lifted out of the path thereof, by reason of which the plunger can freely advance, so as to press the material forward into the baling-chamber and to compact the material already in said baling-chamber. The feed device therefore moves into and out of the plunger-box during the motion of the plunger, such action being automatic.

Connected to the upper side of the plunger in some fixed manner is a plate 24, extending from one side to the other of the plunger-box, and to the outer side of which is hinged a swinging plate, as 25, flexibly connected, as by a rope 26, with the plate 12. The two plates 24 and 25 protect the joint between

the pitman 8 and the plunger 4 to prevent the entrance of foreign matter into the joint from above the same. When the plunger 4 is moved rearward, the under side of the swinging plate 25 will be engaged by an actuating projection, as 27, upon the pitman or rod 8, so as to swing said plate upward and prevent any material being drawn rearward with the plunger from the upper side of the plunger-box. When the pitman has moved a certain distance rearwardly, the projection 27 will pass free of the plate. Beyond this point the plate is further elevated by reason of its connection with a fixed part of the machine. As the plunger moves forward the plate drops by its own weight to its original position.

The pitman or connecting-rod 8 is shown as being loosely connected with the plunger 4, the connection being a free pivotal one and being denoted in a general way by 8^a. Fastened to the upper and lower sides of the pitman adjacent the plunger are arms 8^b of duplicate construction and adapted to coöperate with a plate 8^c, fastened to the inner side of the plunger. Just before the plunger reaches the extreme inner end of its stroke the free ends of the arms 8^b will engage the plunger to cause it to complete the stroke and with a powerful pressure, the strain being taken off the pivotal connection between the pitman and the plunger. The arms 8^b may, if desired, be resilient.

In Fig. 5 the feed device or feeder 19 is represented as connected with a resilient carrier 20^a, the opposite end of the carrier being pivotally connected with the pitman 8. The feed device or feeder 19 operates exactly like the feeder or feed device 19, hereinbefore described, for which reason I have given them corresponding characters. The carrier is represented as consisting of a bowed spring passing between its ends through a guide, as 20^b, carried by the posts 22^a.

What I claim is—

1. A baling-press having a baling-chamber, a plunger, a plunger-box to receive the plunger and in communication with the baling-chamber, a feed device, a carrier for the feed device and connected with the plunger to cause the movement of the feed device into and out of the plunger-box on the reciprocation of the plunger, driving mechanism involving a connecting-rod loosely connected with the plunger, and means on the connecting-rod for acting against the plunger during the last part of the advancing stroke thereof and applying directly thereto a thrust received from the connecting-rod.

2. A baling-press having a baling-chamber, a plunger, a plunger-box to receive the plunger and in communication with the baling-chamber, a feed device, a carrier for the feed device, connected with the plunger to cause the movement of the feed device into

and out of the plunger-box on the reciprocation of the plunger, driving mechanism for plunger, involving a connecting-rod loosely connected with the plunger, and projections 5 on the upper and lower sides of the connecting-rod to simultaneously directly engage the plunger during the final part of the advancing stroke thereof.

3. A baling-press having a baling-chamber, a plunger, a plunger-box to receive the plunger and in communication with the baling-chamber, a feed device, a carrier for the feed device connected with the plunger to cause the movement of the feed device into 10 and out of the plunger-box on the reciprocation of said plunger, a toothed gear in sections, pinions meshing with the teeth of the respective sections, a suitably-driven shaft to which said pinions are fastened, a connecting-rod pivoted at its outer end between the sections of said first-mentioned gear and loosely connected at its inner end with the plunger, and resilient projections attached 15 to the upper and lower sides of the connecting-rod and arranged to directly act against the plunger during the latter part of the advancing movement thereof.

4. A baling-press having a baling-chamber, a plunger, a plunger-box to receive the 20 plunger and in communication with the baling-chamber, a feed device, a carrier for the feed device, connected with the plunger to cause the movement of the feed device into and out of the plunger-box on the reciprocation of the plunger, a plate attached to the 25 upper side of the plunger and extending rearward therefrom, a second plate hinged to the first plate, and actuating means for the plun-

ger involving a connecting-rod jointed to the plunger, said connecting-rod having means 40 to engage the second plate to elevate the same on the rearward movement of the plunger.

5. A baling-press having a baling-chamber, a plunger, a plunger-box to receive the 45 plunger and in communication with the baling-chamber, a feed device, a carrier for the feed device connected with the plunger to cause the movement of the feed device into and out of the plunger-box on reciprocation 50 of the plunger, actuating means for the plunger involving a connecting-rod, a plate fastened to the upper side of the plunger and extending rearward therefrom, a second plate hingedly supported by the first plate, a 55 flexible connection connected with the second plate and also to a fixed member above the same, and means upon the connecting-rod for elevating the second plate on the rearward motion of the plunger. 60

6. A baling-press having a baling-chamber, a plunger, a plunger-box to receive the plunger and in communication with the baling-chamber, actuating means for the plunger involving a connecting-rod loosely connected 65 with said plunger, and projecting means on the connecting-rod arranged to directly act against the plunger on the final advancing movement of said plunger.

In testimony whereof I have hereunto set 70 my hand in presence of two subscribing witnesses.

WILLIAM H. WOODWARD.
